ABSTRACT OF THE DISCLOSURE

A foldable and unfoldable container for dispensing liquid, powdered, solid or semi-solid products to a user capable of flat storage in folded state with consequent space saving prior to use and including generally parallel side and end panels all joined together end to end with transverse scoring between adjacent panels to facilitate ready manipulative movement of the panels into an unfolded open container forming condition for reception of dispensed products. The respective panels along their bottom edges are also provided with depending flaps likewise with scoring along said bottom edges, the flaps being interleaved to be normally between the folded together panels and unfold automatically to a transverse position when the panels are manipulated to open container forming position to form a closed bottom for the opened container and being so shaped as to interlock at such time to retain the container in open condition. A collapsible leakproof liner also may be included which in the folded condition of the panels will be in collapsed state that will expand upon opening of the container to permit leakproof retention of liquid or semi-liquid contents introduced into the opened container through its open top and also permit condition and retention of additives for mixing with and conditioning the contents of the container for use if such are in the form of powdered or liquid concentrates to condition the latter directly for use without requiring transfer of such concentrates to a second container.

FIELD OF THE INVENTION

This invention relates to a collapsible panelled container which can be shipped and stored in a flat or folded condition and for use can be readily manipulated to an open or unfolded condition and at the same time automatically provide a bottom for the opened container. The invention also relates to a collapsible container that can be used in such condition to store a concentrate therein and which upon being manipulated to its open or unfolded condition, will permit introduction of an additive such as a diluent to the concentrate to condition the latter to useful state directly in the opened container.

Because of space considerations, storage and/or dispensing, containers are generally shipped and stored in a flat or folded condition rather than in their open or unfolded condition until their use is required. When it is desired to use the container for receiving products to be dispensed, e.g. at a soda or food counter, the folded container is manipulated by the dispenser from its flat or folded condition to an open or unfolded condition after which the product may be placed in the opened container. For quick change from folded to open condition, simple manipulation is required by the dispenser which automatically will also provide a closed bottom therefor so that the product can be introduced to be carried away by the consumer.

Similarly, it is desirable to provide collapsible containers for packaging and storing concentrated powdered, liquid or semi-liquid in folded containers which can be

2

shipped and stored in folded or collapsed state to the ultimate user who is then required to unfold the container and condition the concentrate by an additive such as a diluent to render it capable of use. Examples of this are powdered coffee or tea, powdered milk, dried soup, dried food mixes, powdered glue, premixed concentrated paint, etc. Upon purchase, the user should be able to unseal the folded container package, open it to unfolded condition quickly and deposit required additive to the concentrate in the opened container without needing to transfer it to a larger container for such purposes.

With many prior art containers that have been used to store products for shipment and sale in flat or folded condition manipulation to an open or unfolded condition has required either placement of a separate closure member over the bottom end of the opened or unfolded container or the manually inter-engagement and locking of flaps connected as adjuncts to the container panels to provide a closed bottom for the opened container to insure that a product stored or to be dispensed in the open container would not spill from its otherwise open bottom end. This obviously has been a burdensome task and, moreover, has slowed dispensation at a counter to the user.

Similarly, heretofore, in particular with concentrated products, no matter whether such product was edible or inedible, frozen or solid, liquid or powder, the ultimate user after opening the container has had to transfer the concentrate therefrom in its relatively small volume to a second container of much larger volume to permit mixing therewith of the required additive to achieve the desired useful product before mixing could be effected. The use of a second container by the ultimate user also is generally burdensome as it is time-consuming and also must be washed and cleaned after use. Often, too, a second container is not available.

It is thus apparent there is a need for a collapsible container that will automatically form a bottom as the container is manipulated from a flat or folded and collapsed condition to an open or unfolded condition and that it will find widespread use. Additionally, if such a container can, in the flat or folded and collapsed condition, be used also to store a concentrate in a leakproof adjunct which latter upon manipulation to an open or unfolded condition of the container can provide a larger volume in the leakproof adjunct that will occur automatically and be supported by the container bottom that desired additive necessary for the desired and final product can be introduced directly to the concentrate in the expanded adjunct in the original container. This will add to the desirability of the collapsible container.

SUMMARY OF THE INVENTION

It is therefore a primary object of the present invention to provide an improved collapsible container having these desirable attributes.

A further object of the present invention is to provide a container that can be shipped and/or stored in a flat or folded and collapsed condition and at the site of ultimate use be readily manipulated to an open or unfolded condition and be provided with members that will then automatically interengage with each other to form a bottom closure for the opened container.

A further object of the present invention is to provide a container that also can be used in flat, folded or collapsed condition to store a concentrate of a final product and which container upon manipulation at the site of use to an open or unfolded condition will also permit introduction into the container of a desired additive necessary to achieve the final product without requiring transfer of

the concentrate to a second container prior to such introduction of said additive.

Briefly, in a first embodiment of the present invention a four-side panelled container also has flaps extending from bottom edges of each of the panels. Each flap is either integral with or permanently fastened to an adjacent flap and normally lies folded against and between the panels. When the container is manipulated from its flat folded or collapsed condition to the open or unfolded condition the said flaps automatically both extend transversely of the flaps and interengage with each other to form a closed bottom for the opened container.

In a second embodiment of the invention, a flexible, collapsible pouch or envelope with an open mouth has its lips attached to the side panels of the collapsed container which is otherwise like that of said first embodiment of the invention. The collapsed pouch or envelope may contain a concentrate in a desired quantity even when within the collapsed container. When such container is manipulated to the open or unfolded condition the pouch or envelope volume will expand automatically substantially to the inner volume of the opened container and also be supported by the flap-formed container bottom so that desired additive may be introduced and combined with the concentrate in the expanded pouch or envelope directly to achieve the finally desired product in the opened container without any need for transfer of the concentrate in the latter to a second container for mixing.

DESCRIPTION OF THE DRAWINGS

Other aspects and features of the present invention will become apparent from the following description and accompanying drawings in which:

FIG. 1 is a perspective view of a collapsed container embodying the present invention;

FIG. 2 is a sectional view taken along line 2—2 of FIG. 1;

FIG. 3 is a sectional view taken along line 3—3 of FIG. 2;

FIGS. 4—6 show successive perspective views of the flaps of the container of FIGS. 1—3 in successive positions of movement as the collapsed container is opened to form a bottom for the container as the container is being manipulated from the folded, flat or collapsed condition of FIGS. 1 and 2 to the open or unfolded condition of FIG. 6;

FIG. 7 shows in perspective and in opened condition a second embodiment of a collapsible container embodying the present invention that may be used to condition an additive to a final product, the concentrate remaining in the same container after its opening and in which the concentrate has been stored and shipped;

FIG. 8 shows in section along line 8—8 of FIG. 7 the opened container into which an additive is being introduced for mixture with the initial concentrate stored in the said opened container;

FIG. 9 is a plan view of the blank for preparation of the container of both embodiments of the present invention, and

FIG. 10 shows in section the container of the second embodiment of the present invention.

DESCRIPTION OF THE PREFERRED EMBODIMENTS

Referring now to the drawings and more particularly to FIG. 1, the reference character 10 denotes a folded or flat container according to the present invention. This container as seen in FIGS. 2 and 3 includes joined side panels 11 and 12 and end panels 13 and 14, all made from a common blank B. Transverse scoring lines 15, 16, 17 and 18 define the respective side and end panels. The side panel 12 in addition includes a flap or tab 19 beyond the scoring line 18 which as seen in FIG. 3 can be adhered or otherwise secured internally to the end panel 14 when the panels are folded together along their respective score

lines as seen in said FIG. 3 to form an endless band and tabular element along the respective scoring lines into closely collapsed condition or unfolded from that condition into an open parallelopiped as seen in FIG. 7, with side panels 11 and 12 parallel to and spaced from each other and end panels 13 and 14 likewise parallel to and spaced from each other. Bottom forming flaps 20 and 21 of substantially like shape are integral with the bottom edges of each side panel 11 and 12 being demarcated therefrom by aligned scoring lines 22 and 23 from respective side panels so that when the container is in the flat or folded condition as viewed in FIG. 2, these flaps 20 and 21 are positioned in folded parallel relationship between the container side panels 11 and 12. Likewise, the end panel 13 includes an integral bottom forming flap 24 demarcated therefrom by a scoring line 25 aligned with scoring lines 22 and 23, and the end panel 14 also includes an integral bottom forming flap 26 demarcated therefrom by a scoring line 27 also aligned with scoring lines 22, 23 and 24. These flaps 24 and 26 likewise lie positioned internally between the side panels when the container is in its flat or folded condition.

As seen in FIG. 9, the respective flaps 20, 21, 24 and 26 are integral with their respective panels 11, 12, 13 and 14 with the scoring or fold lines 22, 23, 25 and 27 aligned and lying between each panel and its respective flap so that folding of the flaps thereon can be effected to allow the flaps to move relative to their respective panels.

As seen in FIG. 9, flap 21 includes wider portion 21A and narrower portion 21B separated by a recessed portion 21C. The wider portion 21A includes an edge 21E that is parallel to scoring line 23 and in extent is slightly less in length than one-half the length of fold line 23. An inwardly slanted side edge 21L extends from the intersection of scoring line 18 and fold line 23 toward edge 21E and joins it. The narrower portion 21B of less width than wider portion 21A includes edge 21N which is also parallel to scoring line 23. Side 21G of narrower portion 21B is generally perpendicular to edge 21N and meets with a slanted edge 21M which latter joins the intersection of fold lines 23 and 17.

Edges 21E, 21K and 21N are all parallel to each other, the edge 21E being furthermost from fold line 23 with edge 21K closest of the three edges to fold line 23. Additionally of the flap portions defined by the three edges 21E, 21K and 21N, portion 21B is narrower than widest portion 21A and the portion 21C of intermediate width lies between said widest and narrowest portions 21A and 21B.

Flap 20 is substantially identical in configuration to flap 21 and those sides and portions on flap 20 that find counter parts in flap 21 have the same lettering subscripts as those edges and portions of flap 21 except that they are prefaced by the reference 20 instead of 21. In flap 20, the portion 20B extends from recessed portion 20C to side edge 20Q which is substantially aligned with fold line 15. A scoring or fold line 20P extends diagonally across flap 20 from fold line 22 to edge 20K defining a triangular portion 20X (shown shaded) which as will be described is ultimately adhered to flap 26.

Flap 24 is seen to be generally trapezoidal in shape with edge 24C parallel to scoring line 25 while edge 24B is aligned with fold line 17. Edge 24C is slightly shorter than scoring line 25 with edge 24H of flap 24 including an elongated slanted part and two short bevelled end edge portions 24G and 24L at different ends of edge 24H. As can be seen in FIG. 9, edges 24L and 24G are approximately parallel to each other but offset slightly and with edge 24C of flap 24 approximately the same distance from scoring line 25 as edge 21K of flap 21 is from fold line 23. A scoring or fold line 24P extends diagonally across flap 24 from fold line 25 to edge 24C defining a triangular portion 24X (shown shaded) which as will be described is ultimately adhered to flap 21.

Flap 26 is a six-sided figure with edge 26B parallel to

fold line 27 and approximately the same distance from it as edge 20B of flap 20 is from fold line 22. Edge 26B is approximately one-half the length of fold line 27 and approximately perpendicular to edge 26C which extends almost the entire width of flap 26 and meets with a slanted edge 26K, the latter extending to the intersection of scoring line 15 and fold line 27. As can be seen from FIG. 9, edge 26K is very small and thus edge 26C and scoring line 15 are nearly aligned. Edge 26D of flap 26 is parallel to edge 26C and meets with a slanted edge 26E which extends to fold line 27. The generally overall widths of flaps 20 and 21 in their widest regions 20A and 21A are somewhat greater than one-half the width of end panels 13 and 14 for purposes to be described.

When it is desired to assemble the blank B defined by the described panels and flaps as shown in FIG. 9 into a container that can be manipulated from a flat or folded condition seen best in FIGS. 1, 2 and 3, to an open or unfolded condition with the various flaps inter-engaging with each other to form a closing bottom for the unfolded container, the blank B is first folded along the scorings 22, 23, 24 and 26 to bring the respective flaps inwardly of their panels. Additionally, flaps 20 and 24 are both folded along their diagonal scorings 20P and 24P and the shaded triangular portions 20X and 24X of said respective flaps are then movable foldably relative to the other portions thereof. The panels 11, 12, 13 and 14 are then folded together along their transverse scorings 15, 16, 17 and 18. Then the flap portion 24X which has been folded along scoring line 24P is glued or otherwise attached permanently to the underside (as viewed in FIG. 9) of flap 21 so that edge 24B of flap 24 lies adjacent fold line 23. Similarly, flap portion 20X which has been folded along scoring line 20P is glued or otherwise attached to the underside (as viewed in FIG. 9) of flap 26 so that side 20Q of flap 20 is adjacent to fold line 27. With each flap 24 and 26 now attached to an adjacent flap 21 or 20 as just described, tab 19 is now attached to the inside face of end panel 14 (FIG. 3). At this time, all four flaps 20, 21, 24 and 26 will project upwardly and lie between the folded together panels 11, 12, 13 and 14 of the container which then is in its folded or flat condition (FIGS. 3 and 4).

When it is desired to open or unfold the assembled container 10, forces in direction of arrows X and Y are externally applied, for example, at the fold lines 15 and 17 of FIG. 3, so that each end panel 13 and 14 will swivel parallelly relative to the other end panel, while each side panel 11 and 12 will move laterally and parallel relative to the other side panel until the container is in the semi-open condition shown in FIG. 5. In this condition, all the flaps 20, 21, 24 and 26 will have begun to rotate outwardly and downwardly on their scorings 22, 23, 25 and 27 towards the bottom of the container with edges 21E and 21L of flap 21 above the widest portion 20A of flap 20 and widest portion 21A of flap 21 directly above the portion 24X of flap 24 adjacent fold line 24P. Of course, section 20X of flap 20 (not seen in FIG. 5) will be beneath the underside of narrower portion 26B of flap 26 having been previously attached thereto. Scoring line 20P of flap 20 will then be beneath flap 26 as triangular portion 20X (not seen in FIG. 5) is attached to the underside of flap 26. Edge 21L of flap 21 will be almost directly above edges 26D and 26E of flap 26. Similarly, portion 20A of flap 20 will be above edges 24H and 24L of flap 24. It is apparent from FIG. 5 that the corner formed by the intersection of edges 24H and 24L serves to ensure that edge 20E of flap 20 will fall above narrower portion 21B of flap 21 as the flaps unfold. In this way, wider portion 20A of flap 20 will always easily and smoothly unfold on top of narrower portion 21B and recessed portion 21C of flap 20.

Continued application of forces along X and Y against scoring lines 15 and 17 will cause edges 21H and 21I of flap 21 and edge 20H and 20I of flap 20 to momentarily

cross each other as seen in FIG. 6. As this is occurring a greater portion of the area of flap 24 adjacent edges 24H and 24L will be beneath widest portion 20A of flap 20 than is shown in FIG. 5. Similarly, narrower portion 21B will overlie a greater portion of flap 24 adjacent fold 24P and the portion of flap 26 adjacent edge 26C will cover a greater portion of flap 20 adjacent fold line 20P than shown for both flaps in FIG. 5. Additionally, widest portion 21A of flap 21 will cover a larger portion of flap 26 adjacent sides 26D and 26E than was previously covered. After edges 21H, 21I and 20H, 20I have crossed each other, continued application of forces to fold lines 15 and 17 will move the container to the fully open or unfolded condition shown in FIG. 6. Here, edges 20I and 21I will lie interlocked adjacent each other with widest portion 20A of flap 20 overlying recessed portion 21C and narrower portion 21B of flap 21. Widest portion 20A of flap 20 will also cover the part of flap 24 that lies adjacent edges 24E and 24L. Similarly, portion 24X of flap 24 and the part of the flap adjacent to portion 24X will be beneath narrower portion 21B of flap 21. Widest portion 21A of flap 21 adjacent side 21L will cover the part of flap 26 adjacent edges 26D and 26E and, also, cover narrower portion 20B and recessed portion 20C of flap 20. The part of flap 26 adjacent side 26C will cover portion 20X and adjacent parts of flap 20. Thus, the overlap of portion 21A of flap 21 relative to underlying portion 20B of flap 20 and similar overlap of portion 20A of flap 20 relative to portion 21B of flap 21 as well as the flap portions 20A and 24X which are secured to respective flaps 21 and 26 as described above will stop further rotary movement of the flaps after they reach a substantially horizontal position perpendicular to the side and end panels, the four flaps over and underlapping then forming a closed bottom for the now-open container. An interlock in this condition is provided by the edges 20I and 21I, which were forced past each other during opening movement of the flaps thus preventing undesired collapse of the opened container.

Thus it can be readily seen that upon manipulation of the folded or flat container shown in FIG. 4 to the fully open or unfolded condition shown in FIG. 6, the flaps of the container will automatically interengage with and over and underlap each other to form a closed bottom for the container. Closure of the opened container can be effected, if desired, simply by applying forces along and externally at the scorings 16 and 18.

For ordinary use, as a carrier for solids such as french fries or other solid food products, the dispenser or other counterman need simply remove a folded container 10 from a pile, apply opening forces to it at X and Y as described and introduce the solid product into the opened container and hand it to the purchaser. If a liquid product is to be dispensed, however, the container additionally may include a flexible pouch or envelope 60 of plastic, flexible leakproof material, preferably inert to contents to be inserted and whose lips are secured suitably as by gluing to upper linear faces of the four panels and which envelope lines their interior. When the container is unfolded to open condition as described, the envelope liner 60 likewise unfolds so that liquid contents can be introduced into the opened container and retained therein.

The foldable container thus far described can also be modified further to serve as a convenient packaging device for concentrates such as powdered food and gelatin products that require mixture with an additive such as a diluent to condition them for use.

If it is desired to use such a modified container as a package to store and ship a concentrate in a compact folded condition which when the package is opened and when the container is manipulated as described to an open or unfolded condition will retain the concentrate and also provide means to receive the required additive such as a diluent necessary to condition it for final actual use, the second embodiment described is further modified in addition to inclusion of the flexible leakproof pouch or

envelope 60 attached to the upper inside faces of the panels of the container. In the described folded condition of the container, the pouch 60 is in collapsed condition and also has a required amount of concentrate C deposited therein (FIG. 10) which, however, is of small volume and does not interfere with folding together of the container, panels and flaps. After insertion of the filling, cover members 61 and 62 secured in place as by sealing tear strips 64 and 63 all are mounted over the ends of the folded container to seal the open ends thereof and prevent leakage of the concentrate filling C. This compact sealed container package 10' permits safe preservation, storage and shipment of compact packages. Thus, the container panels 11', 12', and end panels 13', etc. and flaps 20', 21', etc. in a folded or flat condition as described with respect to container 10 will carry therein the pouch 60' in a collapsed state in the uppermost portion of the folded container 10' as seen in FIG. 10. The concentrate C such as powdered coffee, tea or milk, frozen juice, paste or the like is filled into pouch 60'. The cover members 61 and 62 are releasably held in place over the top and bottom ends of the container 10' as by said tear strips 63 and 64 or by other conventional means.

When it is desired to condition the concentrate C to its useful state, the tear strips 63 and 64 and closures 61 and 62 are removed. The folded container 10' is then manipulated from its flat or folded condition in the same way as the first and second embodiments to the open or unfolded condition similar to that of the first embodiment seen in FIG. 7 with the flaps thereof forming a supporting bottom for the container 10' in the same way as previously described. The bottom of the pouch 60' will be supported by the unfolded flaps and the additive A for the concentrate C then may be introduced into the pouch as seen in FIG. 8. This eliminates the burdensome task of having to ship and store the concentrate in one container, and, for conditioning, to transfer it to a larger volumed container when it is desired to put the concentrate C into use. The concentrates that may be packaged with this embodiment of the present invention can be either edible or inedible, frozen or solid, semi-solid, liquid or powder. Moreover, in the case, for example, of gelatin concentrates the opened package can even be used as a mold for shaping the edible product into an attractive form after introduction of the additive to the opened container.

While specific embodiments of the invention have been described and shown, variations in structural detail within the scope of the appended claims are possible and are contemplated within the scope of the appended claims. There is no intention, therefore, of limitation to the exact abstract and disclosure herein presented.

What is claimed is:

1. An improved foldable container of the type having side panels and end panels joined with transverse first scoring lines between adjacent panels to permit their folding and unfolding, first and second side flaps and first and second end flaps foldably depending about

second scoring lines forming the bottom edges of their respective side and end panels, and a portion of each of two of said flaps being joined respectively to each of the other two flaps whereby opening movement of said side and end panels about said first scoring lines causes automatic unfolding of said flaps about said second scoring lines into a container bottom forming position, wherein the improvement comprises:

10 said first and second side flaps having substantially the same configuration including a first extended portion of selected width, a second extended portion of lesser width and a recessed portion between said extended portions and

15 said first end flap being approximately trapezoidal in shape and having a first edge approximately parallel to said second scoring line, a second edge approximately perpendicular to and intersecting said second scoring line and said first edge, and a diagonal scoring line therein extending from the intersection of the second edge with the second scoring line to a point on said first edge to form a triangular foldable portion which is joined to the first side flap.

20 2. A foldable container in accordance with claim 1 wherein said first end flap comprises:

25 a third edge slanted from said second scoring line to meet said first edge so as to form a corner that, as the container is unfolded, will bear against the first extended portion of the second side flap whereby the first extended portion of the second side flap unfolds above the second extended portion of the first said flap.

30 3. A foldable container in accordance with claim 1 wherein said second end flap comprises:

35 first and second edges perpendicular to said second scoring line,

a third edge parallel to the second scoring line and joining said first and second edges,

40 a fourth edge extending slantedly from one point on said second scoring line and intersecting said first edge, and

45 a fifth edge, longer than said fourth edge, extending slantedly from a second point on said second scoring line and intersecting said second edge.
